UNITED STATES PATENT OFFICE.

HENRY HOWARD AND HARRY J. MORGAN, OF CLEVELAND, OHIO, ASSIGNEES TO THE GRASSELLI CHEMICAL COMPANY, OF CLEVELAND, OHIO, A CORPORATION OF OHIO.

AUTOMATIC MONTE-JUS.

Application filed February 9, 1922. Serial No. 535,416.

To all whom it may concern:

Be it known that we, (1) HENRY HOWARD and (2) HARRY J. MORGAN, citizens of the United States, residing at Cleveland, in the 5 county of Cuyahoga and State of Ohio, have invented certain new and useful Improvements in Automatic Monte-Jus, of which the following is a specification.

Our invention relates to an automatic 10 montejus and more particularly to a montejus for elevating corrosive liquid chemicals from a lower to a higher level.

An object of our invention is to provide a montejus which is simple in construction, 15 efficient in operation and which operates without requiring the attention of an attendant. A further object is to provide a montejus of the type described and which is controlled by a single valve, and more specifically, by a single valve which is not subject 20 to the action of fumes arising from the liquid which is being handled. More specifically an object of the invention is to provide a montejus in which a small amount of air or other 25 pressure fluid is continuously introduced into the liquid receptacle and in which a predetermined increase in pressure in the receptacle opens a valve to connect the receptacle to a source of fluid pressure for evacuating 30 the same.

One embodiment of our invention is illustrated in the accompanying drawings in which—

Fig. 1 is an elevation, partly in section of 35 the montejus;

Fig. 2 is a vertical section of the liquid receptacle and taken at right angles to the section shown in Fig. 1;

Fig. 3 is a vertical section of the liquid receptacle as seen from the rear of Fig. 1, and

Fig. 4 is a vertical section through the regulating valve.

In the drawings, the liquid receptacle or blowcase of the montejus is designated by 45 the numeral 1 and said blowcase is closed by a cover 2. The blowcase may be of any desired shape and is made or lined with material resistant to the acid or other liquid to be handled. To the cover is attached the 50 liquid inlet pipe 3, which is provided with a check valve 4 of any desired type, and a liquid outlet pipe 5 which has its mouth or lower end located near the bottom of the blowcase 1. A casting 6 mounted on the 55 cover 2 has a main port 6' providing com-

munication between the outlet pipe 5 and the delivery or blow-up pipe 7. Depending from the cover 2 is a U-pipe 8 having the bend thereof located above the open mouth of the outlet pipe 5 and having its free end opening 60 in the blowcase adjacent the upper end thereof. The U-pipe 8 which is preferably of the same cross-sectional area as the pipe 7, communicates with the blow-up pipe 7 through a 65 passage in the cover 2 and port 9 in the casting 6. The opening of port 9 into port 6 must be so shaped that any liquid draining down the discharge pipe 7 will not get into the U-pipe and at the same time the normal 70 flow of liquid through 6' when the montejus is discharging must neither materially increase nor diminish the pressure in the U-pipe. All these conditions are provided for in the design shown herein.

Fluid for evacuating the blowcase 1 enters 75 under pressure through a pipe 10 from a regulating valve V which is connected by means of pipe 11 with any suitable source of supply. For convenience, the pressure fluid will be referred to as compressed air though 80 it is to be understood other fluids may be used, such as steam or other vapor or a gas, provided of course, that the fluid used is inert with respect to the liquid being handled.

The regulating valve V, which is located 85 some distance above the highest level of liquid in the supply tank, comprises a casing 12 having ports 13 and 14 which are connected with the source of compressed air and the blowcase 1 by means of pipes 11 and 10, respectively. Communication between the ports 13 and 14 is controlled by a valve 15 which has a stem 15' carrying a diaphragm 16. The diaphragm 16 is clamped to the casing 12 by a cover plate 17 and the space below the diaphragm communicates with port 14 through a port 19 which is controlled by a needle valve 20. The upper end of the stem of valve 15 passes loosely through a port 18 in the cover 17, and through this port 18 the upper side of the diaphragm 16 is subjected to atmospheric pressure. The upper end of the stem 15' carries a nut 21 which is connected to a weighted lever 22. The lever 22 is pivoted to the cover plate 17 by means of links 23 and carries a weight 24 which may be secured to the lever by means of a set screw 25. To prevent acid or other foreign material from entering the valve casing the nut 21 is provided with a depending flange 110

- 28 which encloses a flange 29 formed on the cover plate 17 and constituting an extension of the walls of the port 18. The nut 21 fits the stem 15' somewhat loosely so that it may be turned by hand, and the position of nut 21 on the stem, together with a stop screw 27 which is carried on a yoke 28 straddling the lever 22 determines the amount of throw of the diaphragm 16.
- 10 A port 30 formed in the lower part of the casing 12 constitutes a by-pass around the valve 15 and this by-pass is controlled by a needle valve 31.
- For indicating the quantity of liquid handled a Veedor or other counter 32 is provided, the same being preferably mounted on a bracket 33 carried by the valve casing. The handle of the counter 32 is connected to the lever 22 by means of a link 34.
- 20 In operation, acid or other liquid enters the blowcase 1 from a supply tank or other source of supply through the inlet pipe 3. A limited quantity of compressed air is continuously entering the blowcase through the by-pass 30 and pipe 10. While the filling of the blowcase progresses the air has a free vent through the U-pipe 8 and the blow-up pipe 7. When the incoming liquid level reaches the open mouth of U-pipe 8 and overflows into the same this vent for the air is closed and the pressure builds up inside the blowcase. The diaphragm 16 is subject to the pressure in the blowcase and when the pressure reaches a predetermined point the diaphragm operates to open the main valve 15 thereby establishing free communication between the source of air supply and the blowcase. By means of the adjustable weight 24 on the valve lever 22, the valve 15
- 30 may be set to open at any desired pressure, say five to ten pounds. When the air pressure in the blowcase becomes equal to or greater than that due to the level of the acid in the supply tank the check valve 4 closes and the liquid is forced out through the blow-up pipe 7. As the pressure in the open end of the vent pipe 8 is the same as in the blow-case the level of the liquid in the open end of the pipe 8 will follow down with and will be the same as the level of the liquid in the blowcase. When the liquid level reaches the bend in the U-pipe the compressed air will immediately vent or "kick" through the U-pipe and casting 6, thus releasing the pressure in the blowcase. When the pressure falls below the point for which the valve has been set, the weighted lever closes valve 15 and only a limited quantity of compressed air can enter through the by-pass 30. The cycle of operation is then completed as check valve 4 opens to allow more liquid to enter the blowcase. The rate at which the limited quantity of air enters the blowcase may be regulated by adjusting the needle valve 31 and the needle valve 20 may

be likewise adjusted to throttle down the port 19, thereby preventing too rapid a movement of the diaphragm 16.

It is to be noted that the cross-sectional area of pipe 5 is substantially larger than that of the discharge pipe 7. This construction is essential if the valve actuated counter 32 is to accurately record the quantity of liquid handled. As the quantity of liquid passing out through the U-pipe 8 is insignificant there is substantially no drop in pressure due to friction losses between the open end of pipe 8 and the port 9 in the casting 6. If then the friction losses in pipe 5 cause a drop in pressure between the mouth of the pipe and port 6', this reduction in pressure would be communicated through port 9 to the U-pipe 8 and would cause the montejus to kick before the liquid level in the blowcase falls to the return bend of the U-pipe. The exact point at which the air pressure would be relieved would vary with the friction losses in pipe 5 and this in turn would vary with the rate of flow through pipe 5, which rate depends upon the pressure of the air supply together with the relative size of the discharge pipe 7. It is therefore essential that the pressure drop established in the port 6' of casting 6 due to the flow through pipe 5 shall be the same as the pressure drop in the port 9 due to the flow through the U-pipe, that is to say negligible. We have found that satisfactory results may be obtained by using a 4" pipe for the outlet pipe 5 and a 2" pipe for the discharge pipe 7, or similar relative dimensions for other capacities. The relative size of the U-pipe has no influence on this point but is preferably made the same size as the discharge pipe 7 to facilitate the release of air when the montejus has "kicked." It is to be understood however that other sizes of pipes may be used so long as the condition above stated is satisfied.

It will be observed that the parts of regulating valve are not subject to damage by fumes arising from the liquid being handled since the continuous supply of a limited quantity of air to the blowcase prevents such fumes from entering the air pipe 10.

While we have described what we now believe to be the preferred embodiment of our invention it is to be understood this embodiment is merely illustrative and that various changes may be made in the parts, their relative size, shape and proportion without departing from the spirit of our invention.

We claim—

1. An automatic montejus comprising a receptacle having a liquid inlet provided with a check-valve and a liquid outlet, a source of compressed air, means for continuously supplying a limited quantity of compressed air to said receptacle, and means subject to the pressure in said receptacle

for opening communication between said quantity and under pressure sufficient to source of compressed air and said receptacle when a predetermined pressure has been established.

- 5 2. An automatic montejus comprising a receptacle having a liquid inlet provided with a check valve and a liquid outlet, a source of compressed air, means for continuously supplying a limited quantity of 10 compressed air to said receptacle, a vent port through which such air may escape, means for preventing the escape of air through said vent port when the liquid reaches a predetermined level, and means 15 subject to the pressure in said receptacle for opening communication between said source of compressed air and said receptacle when a predetermined pressure has been established.
- 20 3. An automatic montejus comprising a receptacle having a liquid inlet provided with a check valve and a liquid outlet, a source of compressed air, means for continuously supplying a limited quantity of 25 compressed air to said receptacle, a vent port through which such air may escape, means for forming a liquid seal to close said vent port when the liquid reaches a predetermined level, and means subject to the pressure 30 sure in said receptacle for opening communication between said source of compressed air and said receptacle when a predetermined pressure has been established.
- 35 4. An automatic montejus comprising a receptacle having a liquid inlet provided with a check valve and a liquid outlet, a source of compressed air, means for continuously supplying a limited quantity of 40 compressed air to said receptacle, a U-tube having one end communicating with said liquid outlet and having its other end located within and near the top of said receptacle, and means subject to the pressure in said receptacle for supplying compressed 45 air in quantity and under pressure sufficient to evacuate the receptacle.
5. An automatic montejus comprising a receptacle having a liquid inlet provided with a check valve, an outlet pipe having 50 its mouth near the bottom of said receptacle a source of compressed air, means for continuously supplying a limited quantity of compressed air to said receptacle, a U-tube having one end communicating with said 55 outlet pipe and having its other end located within and near the top of said receptacle, and means subject to the pressure in said receptacle for supplying compressed air in
6. An automatic montejus comprising a closed receptacle provided with a liquid inlet port, an air inlet port, an outlet port and a vent port, an outlet pipe connected to said outlet port and having its mouth 60 near the bottom of the receptacle, a U-pipe connected to said vent port and having its free end located within and near the top of the receptacle and means for connecting said outlet port and vent port to each other 70 and to a discharge pipe.
7. An automatic montejus comprising an open topped receptacle, a cover for said receptacle, said cover being provided with a liquid inlet port, an air inlet port, an outlet 75 port and a vent port, an outlet pipe connected to said outlet port and having its mouth near the bottom of the receptacle, a U-pipe connected to said vent port and having its free end located within and near the top of the receptacle and means for connecting said outlet port and vent port to each other and to a discharge pipe.
8. An automatic montejus comprising a receptacle having a liquid inlet provided 80 with a check valve and a liquid outlet, a source of compressed air, and a regulating valve between said source of compressed air and said receptacle, said regulating valve comprising a casing, a main valve, pressure controlled means for operating said valve, a port having a valve therein and extending between said pressure controlled means and the receptacle side of said valve casing, and a valved by-pass around said main valve.
9. A regulating valve comprising a casing having an inlet and an outlet opening, a valve seat and a valve, pressure controlled means for operating said valve, a valve controlled port in said casing between said pressure controlled means and the outlet side of a casing and a valve controlled by-pass around said valve seat.
10. A regulating valve comprising a casing having an inlet and an outlet opening, 105 a valve seat and a valve, a by-pass around said valve seat, a chamber in said casing, a port in said casing extending from said chamber to the outlet side of said casing, and means in said chamber operative upon 110 a predetermined increase in pressure for opening said valve.

In testimony whereof, we affix our signatures.

HENRY HOWARD.
HARRY J. MORGAN.
